SHORT WAVE DETECTOR SYSTEM

Rene A. Braden, Collingswood, N. J., assignor to
 Radio Corporation of America, a corporation of
 Delaware

Application January 17, 1935, Serial No. 2,141

9 Claims. (Cl. 250—20)

This invention relates to ultra short wave receiving apparatus and has particular reference to means for detecting the received radio frequency energy.

5 It is well known that an electron tube may be so constructed as to operate efficiently when its grid is maintained at high direct current potential in relation both to the cathode and to the plate. Difficulties have been encountered, however, in using two such tubes in push-pull relationship because of the exacting requirements imposed upon the tubes themselves and upon the external connections for obtaining a suitable impedance match between different portions of 10 the system. In order to overcome this difficulty, I have found it desirable to include within one envelope two complete sets of triode electrodes and to provide a suitable dipole antenna connected to my twin-element detector tube through a symmetrical two-wire transmission line having means associated therewith for obtaining standing waves with loops of energy centered in each of the sets of triode electrodes.

Accordingly, it is among the objects of my invention to provide suitable radio receiving apparatus including an antenna, a two-wire transmission line and an electron discharge device for collecting and detecting ultra short wave energy.

30 Another object of my invention is to provide apparatus of the class hereinbefore mentioned in which the balancing of impedances in different portions of the system may be greatly facilitated.

35 Another object of my invention is to provide suitable tuning devices in association with a two-wire transmission line whereby an electron discharge tube having two sets of triode electrodes may be operated as the equivalent of two Barkhausen-Kurz tubes when connected in a push-pull manner.

The foregoing and other objects of my invention will be more fully understood upon reference to the ensuing detailed description when 45 read in connection with the accompanying drawing, in which

Figure 1 shows diagrammatically one embodiment of my invention; and

Fig. 2 shows also diagrammatically another 50 embodiment thereof.

Referring to Fig. 1, I show an electron discharge tube of special construction having an envelope 1 within which are mounted two cylindrical anodes 3, two grids 5 and two filaments 7. Each of the triode sets of electrodes may

be so constituted as to operate in the manner of a Barkhausen-Kurz tube, that is to say, with a high direct current potential impressed upon the grid and with a small difference of potential between the cathode and the plate such as to 5 bias the latter either positively or negatively, according to circumstances.

In the embodiment shown in Fig. 1, the two plates 3 may be mounted adjacent one another. The plate lead 8 is, therefore, conveniently made common to the two plates. This lead is shown connected to an external circuit which includes an adjustable tap 24 on a potentiometer 23 the voltage drop across which may be derived from a low voltage power supply 25, the latter being 15 also connected to the two conductors 27 of a Lecher-wire system comprehending in one part thereof the filaments 7. The grids 5 are also connected in parallel through a lead 19 to a circuit which includes the primary 9 of a suitable transformer 11 and thence to a tap 13 on a potentiometer 15 across which a high direct current voltage may be impressed from any suitable power supply such as that represented at 17. The secondary of the transformer 11 may 25 be connected to any desired utilization circuit.

Connections between the low voltage power supply 25 and the Lecher-wire system may include a rheostat 29 and two radio frequency chokes 31, one in each lead. The conductors 30 27 are preferably disposed quite close to and parallel with one another. As they enter the envelope of the tube, they diverge sufficiently to permit of running the filaments each exactly through the center of its triode system. The 35 filament leads again converge so as to be brought out at the top of the tube into an extension of the Lecher-wire system indicated at 33. A bridging member 35 is adjustably connected across the conductors 33 in such manner 40 that tuning of the circuit may be accomplished. A further means for tuning the circuit is provided by a capacitive bridge including the capacitor 37. The points of connection 39 are also 45 adjustable along the conductors 27.

Any suitable antenna system such as a dipole 50 41 may be symmetrically connected to the conductors 27 at advantageous points for efficient transfer of energy to the electron discharge device.

High frequency energy collected on the antenna and impressed out of phase upon the filaments 7 may be detected through the well known action of the Barkhausen-Kurz tube elements. The high positive potential which is im- 55

pressed upon the grid produces an oscillatory action upon the electrons which are emitted from the filaments. Those of the electrons which have sufficient velocity to be projected 5 through the mesh of the grid are thereafter retarded so that many of them do not reach the inner wall of the plate but are attracted back again to the grid and to the cathode. The radio frequency energy impressed upon the cathode 10 produces a varying difference of potential between the cathode and the other electrodes such that the direct current component between the grid and the cathode is likewise varied. By virtue of the by-pass capacitor 43, one side of 15 which is grounded, the plates are caused to operate substantially at grounded radio-frequency potential. Demodulation of the received energy is obtained in the output circuit, which includes the primary 9 of the transformer 11. The detected signal may, therefore, be utilized in any desired manner.

Referring now to Fig. 2, I show a modification of my invention in which the two triode systems though mounted side by side within one envelope are sufficiently separated from one another so that complete independence of one triode from the other may be maintained. In certain instances it may be desirable to impress different voltages upon the two grids and upon the 20 two plates in order to obtain a satisfactory balance between the two paths of my push-pull system, as will hereinafter appear.

This may be readily accomplished in accordance with the circuit arrangements shown in 25 Fig. 2. The cylindrical plates 45 may be mounted in any suitable manner in accordance with conventional tube design. Within the plates and symmetrically disposed are the usual electrodes including grids 5 and filaments 7, the same as 30 are shown in Fig. 1. In this instance, however, I have shown by way of illustration how the filaments may be connected in parallel instead of in series. The filament potential is here derived from a battery 47, one side of which is 35 grounded and the other side of which is connected to a rheostat 29. From the rheostat direct current is fed to the filaments through a suitable choke 31 and a bridging member 49.

The Lecher-wire system of which the filaments are component parts extends transversely across the cylindrical walls of the vacuum tube envelope. The antenna 41 is adjustably connected to the wires 27. Both of the bridging members 49 and 51 are arranged to be moved 50 into proper position for tuning the circuit so as to produce loops of radio frequency waves on the filaments 7. The return circuit for the filament heating current is led through a center tap on the bridge member 51 and thence 55 through a suitable choke 31a to ground. The high voltage power supply for the grids may be obtained from the source 17, the two sides of which are connected respectively to the terminals of a potentiometer 15a. This potentiometer, however, has two taps 13a and 13b each leading through a different path of a push pull circuit including in each path a primary winding of a transformer 53, and thence to its 60 respective grid 5. The taps 13a and 13b, being independent of one another, may be so adjusted as to impress any desired voltages upon the grids 5 independently of one another.

In like manner the plate voltages impressed 75 upon the two plates 45 may be adjusted each independently of the other, the taps 21a and 21b

on the potentiometer 23a being used for this purpose. The potentiometer 23a is connected between the positive side of the battery 47 and ground and hence supplies any suitable positive or negative bias with respect to the mean potential of the filaments. Two grounded by-pass condensers 43a and 43b are used in connection with the respective plate circuit leads to provide a balanced push pull anode circuit. These serve the same purposes as that of the capacitor 43 10 indicated in Fig. 1. The secondary of the transformer 53 is connected to any desired utilization circuit.

The action of the receiving system for detecting ultra high frequency modulated waves or intermittent waves is substantially the same whether the diagram of Fig. 2 or that of Fig. 1 is followed.

Numerous advantages are obtained from the carrying out of my invention as herein shown 20 and described. The impedance matching of different portions of the system is facilitated by the fact that the parallel wires 27 and 33 of the Lecher-wire system are disposed very close to one another and, within the tube envelope, 25 there is a tapering outwardly and inwardly of the connections to the filaments. This arrangement lends itself to a greatly improved performance of the system since it is easy to obtain symmetry of the electrical characteristics on the 30 two sides of the antenna and transmission lines as well as through the tube elements. The length of the tapered sections as well as the diameter of the conductors used are so chosen as to obtain a rough sort of impedance match before other adjustments are made. The adjustment of the bridging members 35, 37, 49 and 51 along the Lecher-wire system facilitates the matter of building up radio frequency voltage loops upon the filaments. The impedance 35: matching is further facilitated by the adjustable connections of the antenna system along the Lecher-wire system.

It has been found of considerable advantage to apply the radio frequency signal to the filament 45: rather than to the plate because the filament has smaller electrostatic capacity and, therefore, reduces the load upon the line. It is necessary, of course, that the filament supports within the envelope be such that no large amount of capacity 50 is added to that of the filament itself. A higher amplitude of the voltage loop at the filament is thus obtained.

Although I have herein shown two specific 55 embodiments of my invention, it is to be understood that these are merely illustrative and that modifications may be made without departing from the spirit and scope of the invention as defined in the appended claims.

I claim as my invention:

1. A short wave radio receiving system comprising an antenna, a thermionic push-pull detector and a utilization circuit, said detector having all of its electrodes enclosed in one envelope, said electrodes comprising independent 65 cylindrical anodes and each anode having in cooperation therewith an accelerating electrode and an electron emitting cathode, an electric heating source connected with said cathodes, means including independent connections between each of said cathodes and separate portions of said antenna whereby said cathodes are included in said antenna and radio frequency energy may be impressed on said cathodes in out of phase relation, and means including a 70 75

5 suitable energy source for so polarizing said electrodes with respect to one another as to cause said system to detect and to utilize the energy impressed on said antenna.

5 2. In a device for short wave reception, an electron tube comprising a plurality of independent sets of cooperating electrodes each set including a cathode, an anode and an accelerating electrode, a radio energy collecting device, means 10 including a bi-filar transmission line for supplying energy from said collecting device in out of phase relation to the respective cathodes of two of said sets and for causing said sets to operate in a push-pull manner, an output circuit 15 connected to both of said accelerating electrodes jointly, means for supplying operating potentials across said electrodes, means for operating said anodes at substantially a grounded radio-frequency potential, and means for supplying heating energy through said transmission line to 20 said cathodes.

3. A short wave radio receiving system comprising an antenna, a two-conductor transmission line connected to separate portions of said antenna and proportioned to derive energy therefrom which is impressed upon the respective conductors in out of phase relation, an electron discharge tube of the Barkhausen-Kurz type and having two independent sets of electrodes, each set including a cathode, a plate and a grid, the cathode of each set being connected to one of said conductors respectively, means for supplying heating energy through said conductors to said cathodes, an output circuit connected to both of the two accelerating electrodes in common, capacitive coupling means for causing said anodes to be maintained substantially at grounded radio frequency potential, and means including a short circuiting conductor disposed across said conductors at one point and a capacitor disposed thereacross at another point for so tuning the circuit of said antenna, said cathode and said two-conductor transmission line as to establish a voltage loop at substantially the middle of each cathode.

45 4. A short wave radio receiving system comprising an antenna, a Lecher-wire transmission device connected to said antenna, an electron discharge tube comprising two independent sets of electrodes, each set including a cathode, a plate and a grid, each of said cathodes being serially connected into said transmission device, means for so bridging said transmission device conductively near one end thereof and capacitively near the other end thereof as to produce standing waves of energy derived from said antenna and so that loops of said standing waves are maintained on said cathodes, and means for

so polarizing the electrodes of said electron discharge tube with respect to one another that said tube is caused to function as a detector.

5 5. A short wave radio receiving system comprising an antenna, a thermionic balanced detector and a utilization circuit, said detector comprising two sets of electrodes within one envelope, each filament of said electrodes being disposed axially of its set and having lead-in conductors providing circuit connections for the 10 terminals thereof exteriorly of said envelope, a Lecher-wire system connecting said antenna with two of said lead-in conductors, and means including a shorting bar tunably disposed in contact with two others of said lead-in conductors for setting up standing loops of radio waves at points midway of each filament.

6. A system in accordance with claim 5 and having a filament heating source connected to 20 said Lecher-wire system.

7. A system in accordance with claim 5 and having means including an energy source and suitable impedances so connected to said Lecher-wire system as to supply filament heating current thereto while avoiding undesirable 25 dissipation of radio frequency waves impressed thereon.

8. A short wave radio receiving system comprising in combination, an electric discharge device having a pair of spaced substantially parallel straight-wire filaments, a pair of Lecher-wire conductors each including one of said filaments and extending therefrom at opposite ends, filter means for supplying filamentary heating current through said wires, means providing 30 35 adjustable bridging current paths directly between said conductors on opposite sides of said filaments, at least one of said paths being conducting, and a dipole antenna adjustably connected with said conductors on one side of the 40 filaments.

9. In a short wave radio receiving system, the combination of a pair of Lecher-wire conductors, each of said conductors including a straight-wire filament, an anode electrode associated with each filament and a grid electrode interposed between each filament and its anode whereby a pair of triodes is provided, means for operating said triodes as an oscillator with relatively high positive grid bias and low anode-cathode potential, means providing an adjustable bridging connection between said conductors on opposite sides of said filaments whereby said Lecher-wire system is tunable, and a dipole antenna having portions connected each with one of said conductors at adjacent points on the 50 55 one side of said filaments.

RENE A. BRADEN.
